GEORGE F. GILLETTE, OF DETROIT, MICHIGAN.

ENGINE-VALVE.

1,111,827.

Specification of Letters Patent. Patented Sept. 29, 1914.

Application filed April 6, 1914. Serial No. 829,930.

To all whom it may concern:

Be it known that I, GEORGE F. GILLETTE, a citizen of the United States of America, residing at Detroit, in the county of Wayne and State of Michigan, have invented certain new and useful Improvements in Engine-Valves, of which the following is a specification, reference being had therein to the accompanying drawings.

10 The invention relates to engine valves and more particularly to valves of a gyratory type.

It is the object of the invention, first, to obtain a construction in which a perfect seal is maintained between the valve and its seat; second, to provide for a relatively large port area; third, to protect the valve and its seat from the internal heat of the engine; and further, to obtain various 20 specific advantages as hereinafter set forth.

In the drawings: Figure 1 is a longitudinal section through a portion of a multi-cylinder explosion engine to which my valve is applied; Fig. 2 is a plan view thereof; Fig. 3 is a plan view of the valve; and Fig. 4 is a diagrammatic plan view showing a modified arrangement of the cooperating ports in the valve and seat.

A are the cylinders of a multi-cylinder explosion engine; B the pistons therein; and C a detachable head for closing the upper ends of the cylinders. This head C is provided with a flat under face D forming a seat or slide for a gyratory valve 25 plate E. The latter is of a length to extend over all of the cylinders and at its opposite ends is connected with suitable means for imparting the gyratory movement, such as cranks F upon rotary vertical shafts G suitably driven from the engine crank shaft.

The valve E is suitably ported to coöperate with ports in the head C communicating with the inlet and exhaust passages.

45 As shown in Fig. 2, the exhaust passage H is arranged to extend longitudinally on one side of the head C, connecting with each of the exhaust ports I I' etc., while the inlet passage J is arranged upon the 50 opposite side of the head and has lateral extensions connecting with each of the inlet ports K K' etc. The space within the head intermediate these inlet and exhaust 55 passages forms a water-jacket, by means of which the temperature of the valve face is suitably reduced.

To secure efficiency in the operation of the engine it is essential to maintain a perfect seal between the valve and its seat. This I insure by providing each of the cylinders A with a floating head L arranged between the clearance space in the cylinder and the valve plate E. Each of the heads L is preferably fitted within a counter-bore M in the end portion of the cylinder and is packed by peripheral rings N. By reason of the counter-bore the ports formed in the floating heads L, and which register with the ports in the valve seat C, may be made of greater area than would be the case if the floating heads were placed in the cylinder proper.

With the construction as thus far described in operation, the gyratory movement imparted to the valve plate E will cause ports O thereof to pass through an orbit in which they are successively registered with the ports I and K. During this movement the valve plate E is held between the flat face D of the head C and the upper flat face of the floating head L. This head being subjected on its lower face to the pressure within the engine cylinder, will be maintained in sealing contact with the valve plate and will also hold the latter in sealing contact with the face D of the head. Thus a perfect seal will be maintained without regard to the degree of pressure that is developed in the engine cylinders.

To obtain the maximum port area together with a quick opening and closing movement, the coöperating ports in the valve and its seat are preferably of peculiar formation. As illustrated in Fig. 3, the ports in the valve are provided with oppositely-angling sides which are symmetrical with respect to a central line and in the several cylinders these central lines are in different angular relation. Thus with the port O, the central line is parallel to the common plane of the cylinders; with the port O', the central line is perpendicular to this plane; and the ports O² and O³ have their central lines respectively in the planes of the ports O and O', but with the angling sides of the ports oppositely facing. The coöperating ports I and K in the valve seat have their adjacent edges in an angular relation similar to that between the edges of the port O, so that the latter port will have its opposite edges parallel to the edges of

said ports I and K when in a central position therebetween. By reason of this arrangement, a quick opening and closing of the ports is effected with a maximum area 5 when open. The ideal form is illustrated in Fig. 4 where the valve ports are in the form

$$180^\circ - \left(\frac{\text{angular intake period} + \text{angular exhaust period}}{2} \right) + \text{angle of gap},$$

in which the angle of gap is the angular period between the closing of the exhaust port and the opening of the inlet port.

15 The above formula produces a structure in which the edges of the inlet and the exhaust portions of the angle slot are respectively parallel to the chord of the inlet and exhaust angles, while the widths of these two 20 portions of the slot are equal to the segments included by said arcs and chords. As a consequence where the angle of exhaust is greater than the angle of inlet, the port will be correspondingly wider. The requisite 25 port area is obtained by selecting the radius of the arc.

By reason of the fact that the movement of the valve plate is gyratory and that each point in this plate traverses a circular orbit, 30 the edges of the port in the valve plate always remain parallel to the edges of the ports in the valve seat. Furthermore, the movement is such that when the valve port passes into or out of registration with the 35 seat port, it is traveling at right angles to the parallel edges of said ports, which causes the quick opening and closing. On the other hand, the valve port as it approaches full registration with the seat port 40 is approximating a movement parallel to the edges of the ports which causes a relatively long full open period. Expressed in other words, the arrangement is such that the maximum length of open period is maintained 45 while the opening and closing movements are relatively quick. The seat ports are of greater length than the valve ports in order to maintain this long period of full opening, but the width of these ports may 50 be the same as that of the corresponding valve ports.

What I claim as my invention is:—

1. The combination with an engine cylinder having a flat ported valve face, of a 55 valve having a gyratory movement over said face, and a floating head bearing against said valve for maintaining the seal between the same and said valve face.

2. The combination with an engine cylinder, of a floating head in said cylinder, a valve seat, and a valve intermediate said seat and floating head.

3. The combination with an engine cylinder, of a floating head engaging the end of 60 said cylinder, a stationary head having a flat valve face or seat, and a valve inter-

of angular slots having parallel edges P P' P² P³ with an imperforate V-shaped portion P⁴ therebetween. The formula for obtaining the proper included angle between these 10 ports is as follows:

mediate said stationary head and floating head.

4. The combination with an engine cylinder, of a floating head at the end of said cylinder, a stationary ported head having inlet and exhaust passages formed therein, and a valve arranged intermediate said floating head and stationary head.

5. The combination with an engine cylinder having a counter-bored end, of a floating head arranged in the counter-bore of said cylinder, a stationary head having a flat valve face, and a valve intermediate said stationary head and floating head.

6. The combination of an engine cylinder, having a counter-bored end, a floating head engaging said counter-bore and provided with peripheral packing rings, a stationary ported head having a flat face, and a valve intermediate said stationary head and floating head.

7. The combination of an engine cylinder having a counter-bored end, a detachable head for closing said cylinder provided with a flat valve seat, a gyratory valve engaging said valve seat, and a floating head in the counter-bore of said cylinder bearing against said valve.

8. In a multi-cylinder engine, the combination with a plurality of cylinders, each having a counter-bored end, of a common head for said cylinders provided with a flat valve seat, a gyratory valve engaging said seat, and floating heads in the counter-bores of the respective cylinders for bearing against said valve.

9. In an explosion engine, the combination with an engine cylinder, of a floating head engaging the end portion of said cylinder, a stationary head having a flat valve seat, inlet and exhaust passages and a water-jacket intermediate said passages, and a gyratory valve intermediate said floating head and stationary head.

10. In a multi-cylinder engine, the combination with a plurality of cylinders having ported valve seats, of a common gyratory valve for controlling the ports in said seats, the co-operating valve and ports for each of said cylinders being symmetrical with respect to the direction of movement of the valve in the corresponding phase of the cycle.

11. In an explosion engine, the combination with the valve seat, of a gyratory valve,

said valve being provided with a port in the form of an angle slot and said seat having inlet and exhaust ports parallel respectively with the angling portions of said valve port.

- 5 12. In an explosion engine, the combination with a valve seat, of a gyratory valve having inlet and exhaust ports, the edges of each port being parallel and in angular relation to those of the other port, the angle 10 being such that each port is moving substantially perpendicular to its edge when

passing into and out of registration with the coöperating seat port, and is moving substantially parallel to its edge when in full registration with its coöperating port. 15

13. In an explosion engine, the combination with the valve seat, of a gyratory valve, said seat and valve having inlet and exhaust ports respectively having parallel edges and in an angular relation to each other, the 20 included angle being determined by the following formula:

$$180^\circ - \left(\frac{\text{angular intake period} + \text{angular exhaust period}}{2} \right) + \text{angular period between the closing of the exhaust port and the opening of the inlet port.}$$

In testimony whereof I affix my signature in presence of two witnesses.
